EYESHIELD

Raymond F. E. Stegeman, Greece, N. Y., assignor
to Bausch & Lomb Optical Company, Roches-
ter, N. Y., a corporation of New York

Application June 8, 1951, Serial No. 230,526

5 Claims. (Cl. 2-14)

1

This invention relates to eyeshields and more particularly it has reference to eyeshields of the type which embodies a frame bar and a single integral lens member which is detachably secured to the bar.

One of the objects of my invention is to provide an eyeshield of the type described which will be simple in structure, embody a minimum number of parts and hence be relatively inexpensive to manufacture. Another object is to provide an eyeshield having a lens member which may be interchanged easily and without the use of tools. A further object is to provide an eyeshield of the type described having improved means for attaching nose engaging pads thereto. These and other objects and advantages reside in certain novel features of construction, arrangement and combination of parts as will hereinafter be more fully described and pointed out in the appended claims.

Referring to the drawings:

Fig. 1 is a front view of an eyeshield embodying my invention.

Fig. 2 is a sectional view taken on line 2-2 of Fig. 1.

Fig. 3 is a fragmentary view showing the clamping means for holding the lens member.

Fig. 4 is a perspective view of the clamping member and attached nose pads.

Fig. 5 is a rear view of a modification.

Fig. 6 is a fragmentary exploded view showing parts of the lens and frame bar of the modification.

Fig. 7 is a fragmentary front view showing the coaction of the lens and clamping members of the modification.

Fig. 8 is a sectional view taken on line 8-8 of Fig. 5.

A preferred embodiment of my invention is shown on the drawings wherein 10 indicates, generally, an eyeshield having an integral plastic transparent lens member 11. Extending along the top edge of the lens member 11 is the frame bar 12 which has on its under side a groove 13 in which is seated the upper edge of lens member 11. The lower edge of the lens member 11 has a re-entrant or cut-away portion 14 which is adapted to fit over or straddle the nose of the wearer.

The lens member 11 is held in its grooved seat by means of the clamping member 15 which comprises a hook portion 16 which is hooked over the top of bar 12 and two downwardly extending diverging arms 17 which extend along the front surface of lens member 11. The arms 17

2

terminate in rearwardly extending substantially horizontal parts 18 which carry the nose pads 19. The clamping member 15 is made of resilient material so that the resilience urges the arms 17 laterally away from each other and thus holds the parts 18 against the edge of the re-entrant portion 14, as shown in Fig. 3.

The eyeshield may be disassembled readily by urging together the ends of the arms 17 and then unhooking the part 16 from the top of bar 12. The frame bar 12 may be made of any suitable material such as plastic. The usual temples 21 are hingedly carried by the temporal ends of the frame bar 12. The lens member 11 may be made of either clear or tinted transparent material.

In the modification shown in Figs. 5-8, there is provided an integral transparent plastic lens member 31 having on its temporal edges the projections 32 which fit into mating notches 33 formed on the inner side wall of the frame bar 34. The upper edge of lens member 31 is seated in the groove 35 formed in the under side of bar 34 which is formed of a plastic material which is resilient. In attaching the lens member 31 to the bar 34, the projections 32 are fitted into the mating notches 33 and the central part of the bar 34 is then flexed upwardly so that the top edge of the lens member 31 snaps into the groove 35.

30 The clamping member 36 provides additional means for holding the lens and frame bar together and also affords means for supporting the nose pads 37. The clamping member 36 is made of a resilient material and has the hooked or reversely bent portion 38 which is hooked over the top of frame bar 34. Extending downwardly from the hook 38 and along the rear surface of lens member 31 are the two diverging arms 39 to the lower ends of which are attached the horizontal arms or parts 40 which have rearwardly extending parts carrying the nose-pads 37. The lower edge of the lens member 31 has the re-entrant or cut-away portion 41 which is adapted to straddle the nose of the wearer. The upper sides of the re-entrant portion 41 are provided with the horizontal shoulders or notches 42 against which are held the upper sides of the horizontal arms or parts 40. In attaching the clamping member to the eyeshield, the lower ends of arms 39 are flexed together, the hooked part 38 is hooked over the top of bar 34 and when the ends of arms 39 are released the horizontal parts 40 will be positioned under the notches 42 and held there by the resilience of the arms 39.

The usual temples 43 are pivotally carried by the temporal ends of the frame bar 34.

From the foregoing, it will be apparent that I am able to attain the objects of my invention and provide an improved eyeshield which is simple in structure yet efficient in operation. The parts may be readily assembled and the lens member may be inserted or removed without the use of tools. Various modifications can, obviously, be made without departing from the spirit of my invention as pointed out in the appended claims.

I claim:

1. An eyeshield comprising an integral transparent lens member adapted to protect both eyes of the wearer, said lens member having on its lower edge a re-entrant portion adapted to straddle the nose of the wearer, a frame bar extending along the upper edge of the lens member, the under side of the bar having a seat in which the upper portion of the lens member is positioned and a clamping member holding the lens member in said seat, said clamping member being hooked over the top of said bar and in engagement with the edge of the re-entrant portion on the lens member whereby the lens member is detachably held on the frame bar.

2. An eyeshield comprising an integral transparent lens member having on its lower edge a re-entrant portion adapted to straddle the nose of a wearer, a frame bar extending along the upper edge of the lens member, said bar having on its under side a groove in which the upper edge of the lens member is seated, a clamping member holding the lens member in said groove, said clamping member having a part hooked over the top of the bar and a pair of arms extending downwardly from said part and along the lens member and thence horizontally to engage the edge of the re-entrant portion, and a nose engaging pad carried by each of said arms.

3. The construction described in claim 2 in which the re-entrant portion of the lens member has a horizontal notch on each of its sides, and the clamping member is formed of resilient ma-

terial and with the arms extending downwardly in diverging relationship so that the horizontal portions of the arms are held, respectively, under the horizontal notches by the resilience of the member to effect clamping action and thereby detachably hold the lens member in the groove.

4. An eyeshield comprising an integral lens member adapted to protect both eyes of the wearer, said lens member having on its bottom edge a re-entrant portion adapted to straddle the wearer's nose, a frame bar extending along the upper edge of the lens member, the under side of the bar having a groove in which is seated the upper edge of the lens member, holding means hooked over the top of the bar and engaging the edge of the re-entrant portion for holding the lens member in the groove and additional holding means at the temporal portions of the lens member comprising mating projections and notches on the respectively adjacent temporal parts of the lens member and said bar.

5. In an eyeshield having an integral lens member provided with a re-entrant portion adapted to straddle the nose of the wearer and a frame bar extending along the top of the lens member and having a seat in which the upper edge of the lens member is positioned, the combination of a clamping member for holding the lens member in the seat, the clamping member having a part hooked over the top edge of the bar member and other parts engaging the edge of the re-entrant portion in the lens member whereby the lens member is detachably secured to the frame bar.
